CIRCUIT BREAKER

Filed July 23, 1924

2 Sheets-Sheet 2

UNITED STATES PATENT OFFICE.

EDGAR D. MOORE, OF CLEVELAND, OHIO.

CIRCUIT BREAKER.

Application filed July 23, 1924. Serial No. 727,832.

This invention relates to circuit opening devices and has particular reference to a safety switch or circuit breaker embodying certain improvements over those disclosed 5 in my copending applications Serial Nos. 637,176 and 662,663, filed May 7, 1923 and Sept. 14, 1923, respectively, the latter now being Patent Number 1,643,415, dated September 27, 1927.

10 Motors and similar devices are designed to operate at various overloads with corresponding time periods without damage. When protected by the rated fuse, the fuse will permit the momentary current surge 15 present when starting the motor, but will not permit the motor to operate at an overload over an appreciable time which could be done without damage to the motor and is sometimes desirable.

20 As a specific example of the above statements, it might be pointed out that a washing machine using an electric motor as a source of power to operate the washing mechanism and wringer, when protected by 25 a suitable fuse of say 10 amperes, will operate satisfactorily as long as the washing mechanism and wringer are not overloaded. If however, the washing mechanism is being operated and the wringer is operated

30 at a slight overload, the fuse will blow and a new fuse will have to be substituted. If the machine is protected only by the house 35 fuse of much larger capacity of say 25 amperes which is the usual case, the machine

may operate at overloads without blowing the fuse but there is danger in this instance of operating the motor at an overload over too long a period of time so that the motor 40 will be damaged. It is thus apparent that

a motor driven device of this character is not protected at all, or is so protected that slight overloads which are not apt to be dangerous will cause the repeated blowing of fuses during the operation of the machine.

45 It is the general object of the present invention to provide a circuit breaker which shall protect the device in circuit therewith in three distinct ways so that it shall be impossible for the device to be subjected to sudden and dangerous high current surges; an overload current for a greater period of time than the rated time; or repeated current surges due to resetting of the circuit breaker before the source of trouble has been remedied.

Another object is to provide a circuit breaker of the aforesaid character which shall be positive in action and which shall break the circuit with a snap action to prevent arcing. 60

A still further object is to provide a circuit breaker which shall be simple in construction, inexpensive to manufacture and which shall be reliable in operation. 65

With these and other objects in view, the invention consists in the various novel features of construction and arrangement or combination, all of which will be fully described hereinafter and pointed out in the 70 appended claims.

In the accompanying drawings, Fig. 1 is a side elevation of a circuit breaker constructed in accordance with my invention and showing the same in closed circuit position; Fig. 2 is a similar view but showing the circuit breaker in open position; Figs. 3 and 4 are transverse sectional views taken respectively on the lines 3-3 and 4-4 of Fig. 1; Fig. 5 is a side elevation of the circuit breaker showing the main contacts in closed position and the auxiliary contacts in open circuit position; Fig. 6 is an end elevation showing a plurality of circuit breakers mounted in gang formation; and Fig. 7 is a diagrammatic view illustrating the electrical circuit. 75

Describing the various parts by reference characters, 1 denotes the housing for my device which may be in the form of a rectangular metallic box open on one side when the devices are to be assembled in bank formation as will be explained hereinafter, or closed entirely on all sides and ends when used individually. Secured within the housing is a shelf 2 and arranged between this shelf and one end of the housing is a solenoid consisting of a non-magnetic sleeve 3 about which is disposed a winding 4. A plunger 5, having a longitudinal bore 6 80 85 90 95 100 105 therein, is slidably mounted within sleeve 3.

Fastened to the opposite side of shelf 2 is an insulating strip 8 which has fastened thereto a pair of contact springs 9 and 10 which are arranged in spaced relation. Adjacent the end of each contact spring there is fastened a bifurcated arm 11 each of which pivotally receives one end of a link 12 formed from insulating material. The inner ends of these links are recessed as indicated 110 at 13 (Fig. 3) and are arranged in overlapping relation. A bifurcated arm 14 is piv-

totally connected by means of a pin 15 to these links and at the opposite end is provided with a threaded bore to receive a screw 16, the head 17 whereof is positioned within 5 the bore 6 of the plunger. A lock nut 18 serves to hold the screw 16 in adjusted position in arm 14 and a cushioning washer 19 is positioned on top of the lock nut.

In this connection it will be pointed out 10 that screw 16 is slidably mounted in the end of solenoid plunger 5 for a purpose to be referred to more particularly hereinafter.

A metal plate 20 having an insulating section 21 inset therein, is slidably mounted 15 on screws 22 which depend from insulating strip 8. This plate is normally urged toward strip 8 by means of springs 23 which are interposed between the heads of screws 22 and the plate. A pair of spaced contacts 24 and 25 are fastened to strip 8, and plate 20 is adapted to contact therewith to complete the electrical circuit therebetween, the insulating section 21 being adapted to contact with the end of solenoid plunger 5. 20 Plate 20 and contacts 24 and 25 constitute the auxiliary contacts.

Fastened to opposite sides of housing 1 and insulated therefrom by means of insulating blocks 25 are stationary contacts 26 30 and 27 which are disposed in line with the contact springs 9 and 10, and these contacts and contact springs constitute the main contacts. Contact 26 extends through the housing and is fitted with a thumb nut 28 to 35 facilitate electrical connection therewith.

Arranged within the housing 1 adjacent one end thereof is an insulating block 30 to which is pivotally fastened an arm 31 as by means of a screw 32. The outer end 40 of this arm has fastened thereto a thermostatic element 33 which is provided adjacent its upper end with a projection 34 having an inclined edge 35 that is adapted to engage pivot pin 15. A heating coil 36 is disposed 45 about thermostatic element 33 and is adapted to heat said element to cause it to warp so as to disengage projections 34 from pin 15. In this connection it will be noted that arm 31 may be rocked about screw 32 to any desired 50 position and thereby vary the length of time that projection 34 will engage pin 15. One end of heating coil 36 is connected to a binding post 38 which is fastened to housing 1 and insulated therefrom, and the other end of the heating coil is fastened to stationary contact 27.

When the circuit breaker is inserted in series circuit with the electrical device to be protected, current will flow from the line 60 (Fig. 7) to binding post 38, through heating coil 36, stationary contact 27, contact spring 10, thence to auxiliary contact 24, through plate 20 to auxiliary contact 25, then through solenoid winding 4 to contact spring 65 9 and stationary contact 26 to the device to

be protected indicated generally at 40, and thence back to the line. It will be understood of course that current may flow in an opposite direction equally well and the above is merely selected as an example. 70

During the time that current is flowing, heating coil 36 is heating thermostatic element 33, however insufficient heat will be generated to warp element 33 a distance sufficient to disengage projection 34 from pin 15 so long as the current flow is normal. If the electrical device is operated at an overload, sufficient heat will be developed during a period of time, dependent upon the extent of the overload, to 80 warp element 33 and disengage projection 34 from pin 15. The current flowing through the circuit and particularly through solenoid winding 4 will cause solenoid plunger 5 to exert a pull through screw 16 to the 85 arm 14 and links 12 thereby forcibly pulling contact springs 9 and 10 away from their respective stationary contacts 26 and 27 and opening the electrical circuit as shown in Fig. 2. The thermostatic element is preferably set by means of screw 32 so as to disengage pin 15 just in advance of the time that the overload would injure the particular electrical device which is to be protected. 90

If the operator attempts to reset the circuit breaker before the electrical device has cooled and also before the thermostatic element has cooled, no harm will be done. As the resetting handle 39 is pushed inwardly plunger 5 moves inwardly and engages plate 100 20 forcing it away from auxiliary contacts 24 and 25 thereby opening the circuit. Continued inward movement will force the plate 20 into contact with washer 16 and hence force arm 14 inwardly which in turn forces 105 the inner ends of toggle arms 12 inwardly and thereby engages contact springs 9 and 10 with their respective contacts 26 and 27. However projection 34 is out of alignment 110 with pin 15 and hence when the handle 39 115 is released the main contacts will return to open circuit position and the auxiliary contacts will return to closed circuit position. It will thus be obvious that the auxiliary contacts will be maintained in open circuit 120 position until the main contacts are opened, hence no current will flow. If, however, the electrical device to be protected and hence the thermostatic element 33 have cooled sufficiently, then when the operating handle 39 125 is pushed inwardly, the pin 15 will be engaged under the projection 34 and the main contacts will remain closed and the circuit will be completed as soon as plate 20 engages the auxiliary contacts. 130

If there should be a sudden current surge through the circuit sufficient to damage the electrical device, the circuit breaker will be tripped by the increased pull on plunger 5. This increased pull would be sufficient to 135

pull the pin 15 from beneath the inclined edge 35 of projection 34 as the thermostatic element 33 is of a resilient nature and would be deflected to one side. If the operator 5 should attempt to reset the circuit breaker before the cause for the current surge has been removed, no harm will be done as the auxiliary contacts are automatically opened during the resetting of the main contacts 10 and when the plunger handle is released so as to cause the auxiliary contacts to close, the main contacts will be tripped immediately due to the pull on solenoid plunger 5. It is thus impossible for the operator to hold 15 the circuit breaker in closed circuit position.

From the foregoing description it will be obvious that I have provided a practically fool proof circuit breaker which offers maximum protection to an electrical circuit in 20 the following ways:

First. Protection against overloads extending over a period of time greater than the rated period of time for the particular electrical device.

25 Second. Protection against resetting the circuit breaker before the electrical device has cooled to its normal working temperature.

Third. Protection against sudden current 30 surges due to short circuits or overloads greater than the rated overload.

Fourth. Protection against resetting the circuit breaker before the cause of the current surge has been remedied.

35 Fifth. Protection against the operator forcibly holding the circuit breaker in closed circuit position.

The circuit breaker described may be used 40 individually as for example on a washing machine or other electrical device, or a plurality of them may be mounted in gang formation as shown in Fig. 6 and each control a separate circuit. This latter type of installation being particularly useful for 45 house lighting circuits and similar uses.

The circuit breaker provides a quick snap break at the main contacts and hence eliminates arcing at these points. The device is easily reset and requires no special skill 50 or care in use.

Having thus described my invention, what I claim is:

1. A circuit breaker of the character set forth comprising a housing having a solenoid winding therein, a plunger slidably mounted within said winding, a set of main contacts and a set of auxiliary contacts in circuit with said main contacts, a connection between said main contacts and said plunger 55 whereby a predetermined flow of current through said winding will move said plunger to open said main contacts, means for causing said auxiliary contacts to open during the resetting of said main contacts, and a thermal element adapted to be moved

to permit said contacts to open upon an excessive flow of current through said winding extending over a predetermined period of time.

2. A circuit breaker of the character set 70 forth comprising a housing having a solenoid winding therein, a plunger slidably mounted within said winding, a set of main contacts and a set of auxiliary contacts in circuit with said main contacts, a connection 75 between said main contacts and said plunger whereby a predetermined flow of current through said winding will move said plunger to open said contacts, means normally urging said auxiliary contacts to closed position, a connection between said auxiliary contacts and said plunger whereby movement of said plunger to close said main contacts will open said auxiliary contacts, a thermal element normally holding said main contacts 80 in closed position, and a heating coil disposed in operative relation to said thermal element, said coil being in circuit with said winding whereby a predetermined flow of current through said coil and winding will 85 warp said thermal element and permit said main contacts to open.

3. A circuit breaker of the character set 90 forth comprising a housing having a solenoid winding therein, a plunger slidably mounted within said winding, a set of main contacts and a set of auxiliary contacts in circuit with said main contacts, a connection 95 between said main contacts and said plunger whereby a predetermined flow of current through said winding will move said plunger to open said contacts, means for opening said auxiliary contact during the resetting of said main contacts, a thermal element adapted to engage the connection between 100 said plunger and main contacts and normally retain said contacts in closed position, and a heating coil disposed in operative relation to said thermal element, said coil being in circuit with said winding whereby a predetermined flow of current through said coil and winding will 105 generate sufficient heat in said coil to warp said thermal element to disengage said connection and permit said main contacts to open.

4. A circuit breaker of the character set 110 forth comprising a set of main contacts and a set of auxiliary contacts in circuit with said main contacts, magnetic means connected to said main contacts and adapted to open the same upon a current flow in excess of a predetermined value, means connecting said auxiliary contacts with said magnetic means whereby said auxiliary contacts are opened during the resetting of said main 115 contacts, a thermal element operatively connected to said main contacts, and means for heating said thermal element in proportion to said current flow, said thermal element being adapted to be moved to permit said 120

main contacts to open at a predetermined current flow extending over a predetermined period of time.

5. A circuit breaker of the character set forth comprising a set of main contacts and a set of auxiliary contacts in circuit with said main contacts, magnetic means connected to said main contacts and adapted to open the same upon a current flow in excess of a predetermined value, means connecting said auxiliary contacts with said magnetic means whereby said auxiliary contacts are opened during the resetting of said main contacts, a thermal element operatively connected with said main contacts, and a resistance element for heating said thermal element in proportion to said current flow, said thermal element being adapted to warp thereby to permit said main contacts to open at a predetermined current flow extending over a predetermined period of time.

6. A circuit breaker of the character set forth comprising a housing having a solenoid winding therein, a plunger slidably mounted within said winding, a set of main contacts and a set of auxiliary contacts in circuit with said main contacts, a connection between said main contacts and said plunger whereby a predetermined flow of current through said winding will move said plunger to open said main contacts, means for causing said auxiliary contacts to automatically open during the resetting of said main contacts, a thermal element operatively connected to said main contacts in closed position, and means for heating said thermal element thereby to warp said element to permit said main contacts to open upon an excessive flow of current through said winding extending over a predetermined period of time.

7. A circuit breaker of the character set forth comprising a housing having a solenoid winding therein, an armature mounted in operative relation to said winding, a set of main contacts and a set of auxiliary contacts

in circuit with said main contacts, a connection between said main contacts and said armature whereby a predetermined flow of current through said winding will move said armature to open said main contacts, means normally urging said auxiliary contacts to closed position, a connection between said auxiliary contacts and said armature whereby movement of said armature to close said main contacts will open said auxiliary contacts, a thermal element normally holding said main contacts in closed position, and a heating coil disposed in operative relation to said thermal element, said coil being in circuit with said winding whereby a predetermined flow of current through said coil and winding will warp said thermal element and permit said main contacts to open.

8. A circuit breaker of the character set forth comprising a housing having a solenoid winding therein, an armature mounted in operative relation to said winding, a set of main contacts and a set of auxiliary contacts in circuit with said main contacts, a connection between said main contacts and said armature whereby a predetermined flow of current through said winding will move said armature to open said main contacts, means for opening said auxiliary contacts during the resetting of said main contacts, a thermal element adapted to engage the connection between said armature and main contacts and normally retain said main contacts in closed position, and a heating coil disposed in operative relation to said thermal element, said coil being in circuit with said winding whereby a predetermined flow of current through said coil and winding will generate sufficient heat in said coil to warp said thermal element to disengage said connection and permit said main contacts to open.

In testimony whereof, I hereunto affix my signature.

EDGAR D. MOORE.
